UNITED STATES PATENT OFFICE.

LOUIS SAINBERG, OF NEW YORK, N. Y.

FILING DEVICE.

1,278,510.

Specification of Letters Patent. Patented Sept. 10, 1918.

Application filed August 17, 1915. Serial No. 45,896.

To all whom it may concern:

Be it known that I, LOUIS SAINBERG, a citizen of the United States, and a resident of New York, county and State of New York, have invented a certain new and useful Improvement in Filing Devices, of which the following is a full, clear, and exact specification.

This invention relates to a class of devices adapted to permit cards, papers and the like to be filed for convenient use.

My invention has for its object primarily to provide a device designed to be employed as a file whereby cards, papers, and the like may be arranged so as to be preserved in compact and orderly manner for ready reference as occasion may require, and which is so formed that varying quantities of the articles may be accommodated and kept for being easy of access. This is accomplished mainly by providing a receptacle in which are arranged two spaced parallel stationary track members, or guide rods disposed at an elevation above the bottom of the receptacle for supporting the cards, or papers on an even plane when filed in the receptacle, and mounted on these guide rods is a follower, or retaining element adapted to be slidably adjusted back and forth for pressing the articles together to prevent their accidental loss when not in use, or to allow the articles to be spread apart for convenient reference thereto when desired as well as to permit additional papers to be filed in the receptacle.

Another object of the invention is to provide the follower with an integral locking member in the form of a substantially L-shaped extension adapted to frictionally engage the guide rods in a manner so as to automatically lock the follower against accidental movement when pressure is applied on the follower; and a further object of the invention is to provide a filing device of a simple and efficient construction, and which may be made so as to combine unusual strength and durability.

A practical embodiment of the invention is represented in the accompanying drawing forming a part of this specification in which similar characters of reference indicate corresponding parts in all the views, the said invention being more fully described hereinafter, and then pointed out in the claim at the end of the description.

In the drawing, Figure 1 is a perspective

view, partly broken away, of one form of filing device embodying my invention, and

Fig. 2 is an inverted perspective view of the follower used in the device. 60

The filing device has a receptacle 10 which may be of any suitable size and shape, though this receptacle is preferably substantially rectangular, in order to permit cards, papers and the like to be arranged therein 65 so as to be safely kept for convenient reference as occasion may require, the receptacle being formed with a bottom 11, front wall 12, rear wall 13, and side walls 14 and 15.

To the front wall 12 and to the rear wall 70 13 interiorly of the receptacle are secured the ends of two stationary track members, or guide rods, as 16 and 17. The guide rods 16 and 17 are spaced apart in parallel arrangement at a slight elevation above the bottom of the receptacle so as to be on the same relative plane, or in transverse alinement 75 for supporting cards, papers and the like in a manner to prevent all tendency to tilt laterally when placed in the receptacle as 80 will be hereinafter more fully explained. For the purpose of holding the articles in the receptacle against accidental loss when not in use as well as permitting additional articles to be readily filed therein, a slidably 85 adjustable follower, or retaining element, as 18, is provided in the receptacle.

The follower 18 has a plate 19 which is preferably substantially rectangular in shape, and this plate is of less dimension 90 than the interior of the receptacle 10 so as to be freely movable therein. Through the plate 19 adjacent to its lower edge are two openings 20 and 21 which are spaced apart at a distance equal to the spacing of the 95 guide rods 16 and 17, and through these openings are passed the guide rods 16 and 17 for mounting the plate thereon so as to be upwardly disposed in the receptacle 10. The lower edge of the plate 19 is spaced 100 slightly above the bottom of the receptacle, and the openings 20 and 21 of the plate are larger than the diameters of the guide rods to allow the plate to be slidably adjusted back and forth on the guide rods. Serving 105 to permit the follower to be automatically held against accidental movement on the guide rods 16 and 17 when in adjusted positions, on the plate 19 of the follower is provided an integral locking member, as 22. 110

The locking member 22 is preferably in the form of a substantially L-shaped exten-

position composed of an integral strip 23 projecting from the lower edge of the plate 19 toward the front wall 12 of the receptacle 10 and a strip 24 extending upwardly from the 5 forward edge of the strip 23 of the locking member. The strip 23 is disposed somewhat on an acute angle relative to the plate 19 of the follower, and the strip 24 is disposed on slightly an obtuse angle relative to 10 the strip 23. As shown, the plate 19 is thereby disposed on a forward incline, and the strip 24 is likewise inclined in spaced 15 relation to this plate. At spaced intervals through the strip 24 are two openings 25 and 26 which are in register with the openings 20 and 21 of the plate 19, and also through the openings 25 and 26 are passed the guide rods 16 and 17, these openings being somewhat larger than the guide rods to allow the 20 strip 24 to be freely moved on the rods when the plate 19 is moved. By forming the follower 18 in this manner, and disposing the plate 19 and the strip 24 on inclines the guide rods will be frictionally engaged by 25 the edges of the openings 20, 21 and 25, 26 when even a slight pressure is applied on the plate 19, and the follower will then be releasably locked to the rods against accidental movement.

30 When it is desired to use the filing device, the cards, papers, or the like to be filed are disposed in the receptacle between its rear wall 13 and the inclined apertured plate 19 of the follower 18. When the plate 19 is 35 then slightly tilted rearwardly the engagement of the follower with the guide rods 16 and 17 will be released, and the follower may then be slidably adjusted on the guide rods so as to abut against the contents of the 40 receptacle. The contents will thereby be securely held in the receptacle, and when it is desired to refer to one, or more of the filed articles, or when additional articles are to be filed in the receptacle, the follower 18 is 45 operated in a similar manner to free its engagement with the guide rods. The fol-

lower is then directed toward the front of the receptacle, and after the new articles are properly placed in the receptacle the follower is again adjusted correspondingly 50 against the articles. The pressure of the articles against the plate 19 will cause the follower to be automatically locked on the guide rods, as above explained. In this manner a simple, efficient, and durable 55 device for filing cards, papers, and the like for safe keeping as well as for convenient reference is provided.

In the foregoing description, I have embodied the preferred form of my invention, 60 but I do not wish to be understood as limiting myself thereto, as I am aware that modifications may be made therein without departing from the principle, or sacrificing any of the advantages of this invention, 65 therefore I reserve to myself the right to make such changes as fairly fall within the scope thereof.

Having thus described my invention, I claim as new and desire to secure by Letters 70 Patent:—

A filing device comprising a substantially rectangular plate having on one of its longitudinal edges an approximately L-shaped extension integrally formed with the plate 75 so that its intermediate arm is disposed on somewhat an acute angle relative to the plate, while the free arm of said extension is disposed on an obtuse angle relative to its intermediate arm, and spaced pairs of registered holes through the plate and the free arm of the extension, in combination with two rods one arranged in each pair of said 80 openings so that the plate with its extension is movable thereon, and a receptacle in 85 which said rods are fixed.

This specification signed and witnessed this sixteenth day of August, A. D. 1915.

LOUIS SAINBERG.
